UNITED STATES PATENT OFFICE.

WILBERT C. FAWKES, OF PORTLAND, OREGON, ASSIGNOR, BY DIRECT AND MESNE ASSIGNMENTS, OF TWO-THIRDS TO LESLIE H. FAWKES AND ONE-THIRD TO ELLIS E. HERMANN, BOTH OF PORTLAND, OREGON.

WALL-SOCKET AND BOLT.

1,154,580.

Specification of Letters Patent. Patented Sept. 21, 1915.

Application filed January 8, 1914. Serial No. 811,109.

To all whom it may concern:

Be it known that I, WILBERT C. FAWKES, a citizen of the United States, and a resident of the city of Portland, in the county of Multnomah, State of Oregon, have invented a new and useful Improvement in Wall-Sockets and Bolts, of which the following is a specification.

My invention relates to devices for fastening what is known as life belts to the sides of windows on the exterior of the building so as to render the cleaning of the windows a safe occupation.

My invention has for its object to provide a socket for the strap bolts which will not work loose in service by reason of being improperly seated in the material in which it is embedded; and to this end I make my socket with a plurality of laterally and radially expandible anchor portions which will become seated in the material in which embedded in such wise as to hold the socket against lateral movement in any direction.

My invention further has for its object the providing of a socket which is simple and cheap to manufacture, but at the same time so constructing the parts that the socket will be securely wedged in place. In one type of my invention I accomplish the last mentioned result by using a wedge element which will bite itself fast as it were, and thus be held against any return movement.

Other specific features of my invention will be more readily understood from the description thereof hereinafter contained.

In the accompanying drawings: Figure 1 shows a portion of the exterior of a window with a life belt secured in place at its ends as in service; Fig. 2 shows a longitudinal sectional view explanatory of one type of my invention; the socket in this view being shown as permanently embedded in the material in which it is to be affixed; Fig. 3 is a front elevation of my invention of the type shown in Fig. 2, and shows the socket of my invention as in place and the bolt secured in such socket; Fig. 4 is an inner end view of the type of socket shown in Fig. 2, looking in the direction pointed by the arrow 4 in Fig. 2; Fig. 5 is an outer end view of the same socket, thus looking at the

same in the direction pointed by the arrow 5 in Fig. 2; Fig. 6 is a side elevation of the type of socket shown in Fig. 2, the dotted lines showing the interior bore thereof, also the locking rib and the wedge element; Figs. 7 and 8 show modifications in the construction of the mouth of the socket-head, and of the bolt having locking engagement therewith; the interlocking means in this case being of the key-slot and key-lug type; Fig. 9 shows a side elevation of a somewhat different type of my invention; in this case the wedge element is formed of a screw-bolt threaded in a nut non-rotatably held in the socket-head, and the screw-bolt having a conical end serving the purposes of a wedge; Fig. 10 is a plan or top view of the lower part of the last mentioned type of socket; Fig. 11 is an elevation of the nut *v*.

Describing in the first instance the type of my invention shown in Figs. 2 to 6 inclusive: The socket, *a*, is longitudinally divided into parts *a'*, *a''*, along the line *b*, and each of said parts is split at *c*, *d*, thus dividing the shank portions of the socket into laterally and radially expandible anchor portions, *e*, *f*, *g*, *h*, whereby the socket, when embedded in the material, *i*, is rigidly held against lateral movement in any direction, and thus cannot be wiggled loose in service. The socket-head of the socket *j* is provided with an interior transverse locking rib *k*, having a straight face corresponding to the chord of the circle described by the cross section of the cavity of the socket-head. The exterior of the shank of the socket is preferably rifled as at *l*. The bore *m* of the socket is preferably tapered. The socket I usually cast of brass; the wedge *n* I prefer to make of cast iron in the form of a truncated cone, the sides are given a different inclination than the walls of the bore *m*, as shown. The wedge *n* is driven into place by a suitable punching instrument and hammer, and by reason of its described construction its portion *n'* will bite itself into the interior faces of the bore *m*, and thus be securely held against return movement. The bolt *o* is made with a stud *p* of circular cross-section and has a segmental locking flange *q* representing substantially that portion of the circle described by the cavity of the socket

head j , which is supplemental to the locking rib k . It will be noted that the latter is formed at the bottom of the cavity of the socket head. Thus the bolt o can only be inserted in the socket head when its shank o' is lifted into vertical position; and likewise the bolt cannot be removed otherwise than in that position. In this way the bolt o is permitted a rotary movement of substantially $\frac{3}{4}$ of a circle, and cannot become detached from the socket except when purposely detached therefrom. The bolt o is formed with an eye o^2 for receiving the snap hooks r of the ends of the strap s .

15 The construction of my invention in the type thereof shown in Figs. 7 and 8 is substantially like that above described except that the socket-head j' is formed with a locking flange k' having a key slot k^2 , and 20 the stud p' of the bolt o^3 is made with a key lug t , instead of flange q , as shown in Fig. 2.

In the types of my device shown in Figs. 9 and 10, the differences are these: The two parts of the socket u , u' are spaced apart at 25 u^2 , so as to accommodate the lateral portions v of a nut v' , non-rotatably seated between the two parts of the socket head u^3 , as shown in Fig. 9. In the nut v' is threaded a bolt w having an eye w' . The end w^2 30 of said bolt is made of conical form so as to operate like the wedge element n to force the split anchor-members of the shank of the socket laterally and radially apart, in order to firmly secure the socket in place in 35 the material in which embedded.

In the last described type of my invention, the socket could be removed from the cavity of the material in which it is placed, while in the first described types of my invention 40 the socket would be irremovable; and this, in some instances, is very desirable, preventing tampering with the socket, which would introduce an element of unsafety. The opposed faces of the socket parts, a' , a^2 , along 45 their dividing line b , are respectively provided with wedge-shaped lugs x and corresponding cavities y , for holding these socket parts against longitudinal movement upon each other.

50 I claim:

1. In a device of the character described, a longitudinally divided socket comprising a socket-head and a shank, the shank part of each member being split to provide laterally expandible anchor portions; one part of the socket being provided with a wedge shaped lug (or lugs) and the other with a corresponding cavity (or cavities) to hold the socket parts against longitudinal movement upon each other; and a conical wedge element inserted in the socket.

2. In a device of the character described, a longitudinally divided socket comprising a socket-head and a shank, the shank part of each member being split to provide laterally

expandible anchor portions; means for locking the parts of the socket against longitudinal movement upon each other; and a conical wedge element inserted in the socket and made of harder material than the socket. 70

3. In a device of the character described, a longitudinally divided socket comprising a socket-head and a shank, the shank part of each member being split to provide laterally expandible anchor portions; means for locking the parts of the socket against longitudinal movement upon each other; and a conical wedge element inserted in the socket and whose sides are of different inclination 75 than that of the bore of the socket. 80

4. In a device of the character described, a longitudinally divided socket comprising a socket-head and a shank, the shank part of each member being split to provide laterally expandible anchor portions; means for locking the parts of the socket against longitudinal movement upon each other; a conical wedge element inserted in the socket; and a bolt having locking engagement with the socket-head and only removable therefrom 90 when lifted to vertical position.

5. In a device of the character described, a longitudinally divided socket comprising a socket-head and a shank, the shank part of each member being split to provide laterally expandible anchor portions; means for locking the parts of the socket against longitudinal movement upon each other; the shank having a tapering bore; a wedge element comprising a nut non-rotatably held in the socket-head, and a screw-bolt threaded in such nut and formed with a conical wedge-end for expanding the anchor portions of the shank of the socket by the inward movement of the screw bolt. 100

6. In a device of the character described, a longitudinally divided socket comprising a socket-head and a shank, the shank part of each member being split to provide laterally expandible anchor portions; means for locking the parts of the socket against longitudinal movement upon each other; a conical wedge element inserted in the socket; the socket head formed with an interior transverse locking rib having a straight face corresponding to a chord of the circle described by the cross section of the cavity of the socket head, and a locking bolt formed with a segmental locking flange representing substantially the remaining area of said circle. 110

7. In a device of the character described, a longitudinally divided socket comprising a socket-head and shank, a conical wedge element inserted in the socket, a bolt adapted for being inserted in said socket and rotated therein, interlocking portions on the interior of the socket head and on the bolt adapted for locking the latter against withdrawal except when rotated to its highest position. 125

8. In a device of the character described,

a longitudinally divided socket comprising a socket-head and shank, a conical wedge element inserted in the socket; the socket-head being formed with an interior, transverse locking-rib having a straight face corresponding to the chord of the circle described by the cross-section of the cavity of the

socket-head and a locking-bolt formed with a segmental locking flange representing substantially the remaining area of said circle. 10
